UNITED STATES PATENT OFFICE.

KARL LARS ESAIAS THUNHOLM, OF ÖREBRO, SWEDEN.

EVAPORATING APPARATUS.

1,324,417.

Specification of Letters Patent.

Patented Dec. 9, 1919.

Application filed August 2, 1918. Serial No. 247,960.

To all whom it may concern:

Be it known that I, KARL LARS ESAIAS THUNHOLM, a subject of the King of Sweden, and residing at 21 Västra Gatan, 5 Örebro, Sweden, have invented certain new and useful Improvements in Evaporating Apparatus, of which the following is a specification.

The evaporating apparatus which are at 10 present generally employed for evaporating liquids coagulating at higher concentrations are, as is well known to those skilled in the art, provided with a number of outwardly heated, narrow tubes located vertically in a 15 closed vessel and through which the liquid is forced from below and upward or vice versa in such manner that the liquid principally flows on the inner walls of the tubes leaving the central portions of the same free in order 20 that the generated steam may freely escape and that the evaporating apparatus may thus have the highest possible capacity.

From theoretical point of view such evaporating apparatus have great advantages 25 over other types of evaporators, but in several respects they have considerable drawbacks which are due to the fact that the tube surfaces, on evaporating such liquids that have a tendency to coagulate in concentrated 30 condition, very soon become covered with a heat insulating deposit making it necessary from time to time to stop the work of the apparatus for removing said deposit from the tubes.

35 My present invention now has for its object an evaporating apparatus, principally adapted to be used for evaporating such liquids that have a tendency to coagulate at higher concentrations, for instance waste 40 sulphite cellulose lye, and in which, at the same time as it provides for maintaining a large total steam generating liquid surface and free escape for the generated vapors, a continuous cleaning of the heat transmitting 45 surfaces is effected.

The apparatus consists of a closed receptacle comprising a number of compartments with double horizontal bottoms, the inner space between said bottoms forming a heating chamber. The double bottoms are provided with holes in which a collar or other communicating device is located, said collar extending a certain distance into the compartment to which the bottoms belong.

55 Through this collar the vapors generated from the liquid having the form of a hori-

zontal layer on the upper bottoms escape to the next compartment and so on until it leaves the receptacle through a discharge conduit. Each collar is at one place provided with a recess forming an overflow for the liquid from one compartment to the next lower compartment. On a central vertical shaft passing throughout the apparatus there are located scrapers one for each compartment, said scrapers being adapted to rotate with the shaft and to be displaced in the longitudinal direction of the same for the purpose that they may drag on the upper bottoms under the action of their whole weight and, thus, remove any deposits from 60 said bottoms. In order to facilitate the rotation of said scrapers they are preferably provided with a number of recesses, said recesses being located in such a manner that 65 the recesses on one arm are located at different distances from the shaft than those on the other arm, in order that those parts of the bottom which are, due to said recesses, not acted upon by the one arm of the scraper 70 will be acted upon by the other one. It is convenient to locate the holes in the bottoms and also the collars zigzag. It is also suitable to locate the overflows at diametrically 75 opposite sides of adjacent collars.

In the present apparatus the liquid is, 80 during the evaporation, maintained divided into a number of horizontal layers of uniform thickness. During the evaporation thus a uniform lowering of the whole liquid 85 surface takes place and currents are formed within each liquid layer from the point where fresh liquid is supplied to every point of the surface, these currents being most powerful in the direction to the point where 90 the overflow takes place. Due to these currents the thinner liquid being supplied from above will immediately be thoroughly 95 mixed with the more concentrated liquid on the bottom. Such a thorough and immediate mixing is especially necessary on concentrating such liquids that have a tendency to coagulate at higher concentrations, since in other cases the liquid would be concentrated to dry thickness at some points of the 100 surface and the transmission of heat at such points be rendered impossible. The liability of the liquid to flow directly to the overflow is also counteracted by the action 105 of the rotating scrapers.

110 Other features of my present invention are made clear by the following description

of a form of embodiment of the apparatus shown on the accompanying drawing.

Figure 1 is a vertical section through the apparatus. Fig. 2 is a plan view of a 5 scraper.

The apparatus is built up by a number of sections 1 each of which forms a receptacle like body provided with double bottoms 2 and 3. The upper receptacle is provided 10 with a cover 5 and the lower one with a bottom 6. Each receptacle is at its upper and lower ends provided with a surrounding flange 4 and, when assembled, they rest on said flanges which can be held together 15 and tightened in any convenient manner. Centrally in the apparatus is journaled a vertical shaft 7 located at its lower end in a bearing 8 and at its upper end in a bearing 9. The shaft is provided at its upper 20 end with a belt pulley 10 or any other means for imparting movement to the same. The shaft is running through holes in the bottoms, the holes in the different pairs of bottoms 2, 3 being preferably located zigzag. 25 Through the holes of each pair of bottoms 2, 3 is inserted a tube shaped collar 22 which is tightly fastened to both bottoms. This collar extends to a certain distance above the bottom 2 and is provided with a recess 30 14 forming overflow for the liquid. The recesses 14 are preferably located at diametrically opposite sides of adjacent collars. On the shaft there are located a number of scrapers 11 one for each bottom 2. They 35 ought to be made of a material which is softer than that of the bottoms 2 in order that the latter may not be worn out too easily by the scrapers dragging on the same during the rotation of the shaft. The 40 scrapers are provided with recesses 12 in order to facilitate the rotation of the same, said recesses being located on one arm of the scrapers at another distance from the shaft than on the other arm in order that during 45 a whole turning of the scrapers, every point of the bottoms may be acted upon by the same. These recesses may be of different length and form on different scrapers as is shown in the drawing. The scrapers 50 ought, in the horizontal projection, to have the shape shown in Fig. 2, according to which they are at the ends curved forward in the direction of movement in order that, on rotating against the liquid, a force 55 component may be effected counteracting the centrifugal force for preventing the liquid surface from becoming higher at the periphery than nearer to the center. The scrapers are located on the shaft in such a manner 60 that they can be freely displaced in the longitudinal direction of the same. By this arrangement the scrapers are adapted to rest freely on the bottoms 2 and act on the same with their whole weight. For this 65 purpose their hubs are provided with a

groove 13, Fig. 2, and the shaft 7 with a corresponding longitudinal key.

In the cover 5 there is provided an inlet tube 15 for the liquid to be concentrated, and a discharge tube 16 for the vapors 70 formed. 18 is a tube through which the heating medium, for instance steam, is supplied. The steam is from this tube introduced into the heating chambers between the bottoms 2 and 3 through branch pipes 75 19. These pipes open into the heating chambers at such a distance above the bottoms that the water of condensation cannot flow off through the same. After having passed through the heating chamber and given off its heat to the liquid through the bottoms 2 the steam is led off through pipes 20 situated at the same level as the bottoms 3 so that the water of condensation is also led off through the same. The pipes 20 open 80 into a discharge tube 21. The concentrated liquid is led off through tube 17 at the lower part of the apparatus.

The apparatus works in the following manner: The liquid is supplied through 90 pipe 15 while the shaft 7 is rotated and the heating medium is introduced through the tubes 18 and 19. The liquid rises in the uppermost compartment, at the same time as it partially evaporates, until a part of the 95 same flows off through the overflow 14 and flows through the collar 22 down on the bottom 2 of the adjacent compartment where it evaporates and so on throughout the whole apparatus. The vapors generated are led upward through the collars 22 without resistance and are then led off from the apparatus through the conduit 16. As stated above, the scrapers have the object of not only removing any deposits from the bottoms 2, but also to impart motion to the liquid and thus mechanically facilitate the 100 escaping of the steam bubbles formed at said bottoms. The liquid becomes gradually concentrated as it descends from one bottom 2 110 to another, and finally when it reaches the bottom 6 it has obtained the desired degree of concentration. The concentrated liquid is then discharged through conduit 17. By varying the supply of liquid and of heating 115 medium different degrees of concentration can be obtained. The supply of heating medium to the different heating chambers can also be varied by means of valves provided in the pipes 19.

In the case that steam is used as a heating medium the tube 18 can be fed with fresh steam, waste steam or wholly or partially with steam escaping from the conduit 16 after having been compressed so as 125 to get higher pressure and temperature. The heating may of course also be effected by means of electrical resistances located in the heating chambers.

It is obvious that the detail constructions 130

shown may be varied without departing from the scope of the invention.

Having now described my invention, what I claim as new and desire to secure by Letters Patent is:

1. The herein described evaporating apparatus, including a closed receptacle composed of a plurality of sections forming compartments and provided with double bottoms having openings therein, collars secured about the openings in the double bottoms and projecting thereabove into the adjacent compartment and provided in their upper edges with overflow recesses, a vertical rotatable shaft in the receptacle, means for rotating the shaft, scrapers on the shaft for moving about the upper portion of each double bottom, the spaces between the double bottoms constituting heating chambers, means for controlling the passage of a heating agent through the heating chambers, means for supplying liquid to the upper part of the apparatus, and means for discharging concentrated liquid from the bottom of the apparatus.
2. The herein described evaporating apparatus, comprising a closed receptacle, a number of compartments in said receptacle, horizontal double bottoms to each compartment, a heating chamber between said double bottoms, holes through said double bottoms, a collar passed through said holes and secured to the bottoms, said collar extending a distance into the compartment, a recess in said collars forming overflow for the liquid to next compartment, said collars also forming means for leading off vapors from the compartments, a central, vertical shaft through the apparatus, means for rotating said shaft, scrapers on said shaft adapted to rotate with the same and to drag on each upper bottom, recesses in said scrapers, means for supplying a heating agent to each heating chamber, means for discharging the heating agent and water of condensation from each heating chamber, means for supplying liquid to the upper compartment, means for leading off vapors from the same and means for discharging concentrated liquid from the lower part of the apparatus, substantially as described and for the purpose set forth.
3. An apparatus as claimed in claim 1 wherein the openings in each double bottom are arranged in registration and the adjacent collars are arranged in staggered relation.
4. An apparatus as claimed in claim 1 wherein the overflow recess in each collar is arranged at a point diametrically opposite the recess in the adjacent collar.

In testimony whereof I have affixed my signature in presence of two witnesses.

KARL LARS ESAIAS THUNHOLM.
